AZINE COMPOUNDS AND MATERIALS
COLORED THEREWITH

Joseph B. Dickey and James G. McNally, Rochester, N. Y., assignors to Eastman Kodak Company, Rochester, N. Y., a corporation of New Jersey

No Drawing. Application July 24, 1940,
Serial No. 347,219

6 Claims. (Cl. 260—243)

The present invention relates to azine compounds and to materials colored therewith. More particularly, it relates to azine compounds having the general formula:

wherein Z_1 represents the non-metallic atoms necessary to complete a benzene nucleus, Z_2 represents the non-metallic atoms necessary to complete an aryl nucleus selected from the group consisting of a benzene nucleus, a naphthalene nucleus, and a phenanthrene nucleus, and X represents a member selected from the group consisting of an oxygen atom, a sulphur atom, a nitrogen atom, and an imide group, and wherein Z_1 contains at least one alkylamino group, and Z_1 and Z_2 together contain at least one acid ester of phosphorus group joined to the omega carbon atom of a non-cyclic organic sidechain. These compounds are usually prepared in the form of their quaternary salts such as the chloride, sulfate, chlorate, sulfonate, and the like. While they are considered mostly as having the p -quinonoid structure, it will be understood that they are subject to tautomeric change to the o -quinonoid form.

More specifically, the acid ester of phosphorus group can be represented by the general formula:

wherein n represents zero or the numeral 1. R_1 and R_2 each represents an amino group, an alkylamino group such as methylamino, ethylamino, propylamino, butylamino, cetylamino, methoxyethylamino for example, and the group $-OZ$, wherein Z represents hydrogen, an alkyl group such as methyl, ethyl, propyl, butyl, cetyl, an alkali forming metal such as sodium, potassium, calcium, barium, a nitrogen containing basic group such as an ammonium radical, and organic group such as an ammonium radical, and organic amine salts of the free acid such as the dimethylamine salt, the ethanolamine salt, the diethanolamine salt, the ethanolamine salt, the diethanolamine salt for example, and X represents an atom

of oxygen or an atom of sulphur. The sidechain can be represented by the radicals such as

and other similar kind of radicals. Further, the nuclei Z_1 and Z_2 , in addition to Z_1 containing at least one alkylamino group and Z_1 and Z_2 together containing at least one acid ester of phosphorus group in a sidechain, can also contain other mono-va lent substituent groups such as methyl, ethyl, propyl, methoxy, ethoxy, amino, methylamino, ethylamino, hydroxyl, and atoms such as chlorine and bromine.

We have found that the azine compounds above described form a valuable series of coloring agents for textile materials such as organic derivatives of cellulose, wool, silk and mordanted cottons, as well as dyes for anti-halation backing compositions for photographic films. The tinting power of our new dyes range in color from green to blue. The materials colored by these dyes exhibit good stability to light and atmospheric exposure. The water-soluble feature of our new dyes is particularly advantageous in the case of anti-halation backings, since the dyes can be removed quite easily during the process of development and fixation of the photographic film.

It is an object of our invention, therefore, to prepare the compounds described. A further object is to color textile materials therewith. Another object is to prepare backing compositions containing our new dyes.

The azine compounds of the invention can be prepared by starting initially with the dye nucleus already formed and containing one or more substituent groups having a hydroxyl group, or, groups such as amino which can be converted to a hydroxyalkylamino group by reaction with an alkylene oxide such as ethylene oxide, or, nuclear hydroxyl groups which can be converted to a hydroxyalkoxy group by reaction with an alkylene chlorhydrin, and phosphating the hydroxyl group. Suitable phosphating agents include compounds such as phosphorus oxychloride,

phosphorus sulfochloride, phosphorus trichloride, phosphoric acid, tetraphosphoric acid, thiophosphoric acid, phosphoric anhydride, phosphorus oxydichloride, methoxy phosphorus oxymonochloride, amino phosphorus oxydichloride, methyldiamino phosphorus oxydichloride and various other alkoxy and substituted amino phosphorus compounds. The phosphating intermediates may be prepared as described in McNally and Dickey U. S. Patent No. 2,183,998, December 19, 1939. Another method of preparing the dye compounds of the invention is to start with intermediates such as a paranitrosoaniline and condense it with a compound such as a 2,6-diphenyl-naphthylene diamine, a dialkyl-m-amino-p-cresol, and the like, or, start with a para-alkylamino-diphenylamine and condense it with a compound such as phenanthrene for example. The phosphorus acid ester groups can be present originally in one or both of the starting materials or such acid ester groups can be formed by simple esterification of nuclear hydroxyl groups or hydroxyl groups contained as substituents on the omega carbon atom of non-cyclic organic sidechains.

The following examples further illustrate the compounds of our invention, their methods of preparation and their applications. It will be understood that these examples are not intended to limit our invention.

Example 1

1 mole of 3-hydroxy-7-amino-paraphenothiazine chloride is treated with approximately 2 molar equivalents of ethylenchlorhydrin, and the product obtained is dissolved in pyridine and condensed with 2 molar equivalents of methoxy phosphorus oxydichloride dissolved in pyridine or dimethylaniline. The reaction is completed by warming, after which the halogen remaining on the phosphorus is hydrolyzed with aqueous sodium carbonate, from which the ammonium salt may be prepared. The dye obtained has the probable formula:

and colors cellulose acetate blue shades from an aqueous solution which may contain salt.

In place of methoxy phosphorus oxydichloride there can be substituted an equivalent amount of methoxy phosphorus dichloride, in which case there is obtained the trivalent phosphorus dye 3-β-methylphosphitoethoxy-7-β-methylphospitoethylamino-phenothiazine chloride. Various other phosphating agents may be used including phosphorus trichloride.

Example 2

1 mole of 1-methylcarboxy-3,4-dihydroxy-7(di-β-hydroxyethyl) amino-paraphenoxazine chloride is dissolved in pyridine and treated in the cold with approximately 1.1 moles of phosphorus oxychloride. The reaction is completed by warming, after which the halogen remaining on the phosphorus atom is hydrolyzed with aque-

ous sodium carbonate. The dye obtained has the formula:

and colors cellulose acetate and mordanted cotton blue shades from an aqueous solution of the dye. Any desired basic salt such as ammonium, piperidine, methylamine, calcium, and the like, can be prepared. In place of the phosphorus oxychloride employed in the above example, there may be substituted phosphorus sulfochloride, in which case there is obtained the corresponding thiophosphoric acid ester derivative.

Example 3

In a manner similar to that described in Example 2, there is condensed together approximately equal molar proportions of 1-methylcarboxy-3,4-dihydroxy-7-cetyl-β-hydroxyethylamino-paraphenoxazine chloride and phosphorus trichloride, the compound obtained being a phosphorus acid ester having the formula:

and coloring cellulose acetate and mordanted cotton blue shades from an aqueous solution of the dye.

Example 4

1 mole of gallocyanine is reacted in the cold, in the presence of an oxidizing agent such as air, with approximately 1 mole of amino-ethyl phosphate. After the initial reaction is complete, the product is decarboxylated by heating at 100° C. The dye obtained has the probable formula:

and colors cellulose acetate blue shades from an aqueous solution which may contain salt.

Example 5

1 mole of 4-nitroso-1-ethyl-β-dimethyl phosphatoethylamino-benzene is reacted in boiling methyl alcohol with approximately 1 mole of dimethyl-m-amino-p-cresol. When the reaction is complete, the dye is crystallized, filtered off, washed and dried. The dye obtained has the probable formula:

and colors cellulose acetate blue shades from an aqueous suspension of the dye.

In place of 4-nitroso-1-ethyl- β -dimethyl phosphatoethylamino-benzene, there can be substituted an equivalent amount of 4-nitroso-1-(di-phenyl phosphitoethyl) amino-benzene, the product obtained having the probable formula:

and coloring cellulose acetate, wool and silk blue shades.

Example 6

1 mole of 2-(N-di- β -hydroxyethyl) phenylene-p-diamino-3-amino-7-(di- β -hydroxyethyl) amino-phenazine chloride is treated in pyridine with 2 molar equivalents of phosphorus oxychloride. The resulting chloro compound is hydrolyzed with sodium carbonate, neutralized with mineral acid and the diethanolamine salt prepared. The dye obtained has the probable formula:

and colors cellulose acetate violet shades from an aqueous solution which may contain salt.

Example 7

1 mole of 2-amino-4-ethyl- β -disodium phos-
phatoethylamino-diphenylamine is heated with
approximately 1 mole of phenanthrenequinone in 40
6000 c. c. of acetic acid on a water bath until a
portion of the reaction mixture boiled with an
excess of water and acidified with hydrochloric
acid shows no increase in intensity of color. The
melt is then boiled with 6000 c. c. of water, acidified
with hydrochloric acid and salted out. The
dye obtained has the probable formula:

and can be employed for printing calico orange shades.

Similar dye compounds can be prepared by employing other phosphorus ester derivatives. For example, the condensation of molar equivalents of 2-amino-4-butyl- β -dimethyl phosphitoethyl-amino-diphenylamine and phenanthrene-quinone gives the dye compound 9-phenyl-12-butyl- β -dimethyl phosphitoethylamino- α , γ -di-benzophenazine chloride which colors silk, wool and mordanted cotton orange shades.

Example 8

1 mole of 4-nitroso-1-ethyl- β -(diethylamino) phosphorus oxyethylaminobenzene hydrochloride is heated in alcohol with approximately 1 mole of 2,6-diphenyl-naphthalene diamine. When the reaction is complete, the alcohol is concentrated

and the dye allowed to crystallize from solution. The dye obtained has the formula:

10 and colors cellulose acetate, wool and silk green shades.

A number of other similar kind of dyes can be made by the processes described in the preceding examples including the following.

Cellulose acetate is colored green shades from

an aqueous solution which may contain salt. Wool is also colored green shades from an acid

35 Wool is also colored green shades from an acid bath.

Cellulose acetate is colored blue shades from an aqueous solution of the dye which may contain salt.

Cellulose acetate is colored green shades from an aqueous solution which may contain salt.

Cellulose acetate, wool and silk are colored blue shades from an aqueous solution of the dye.

The new dye compounds of our invention can ordinarily be applied to the textile material to be colored directly from an aqueous solution of

the dye which may contain salt. As textile materials there can be employed organic derivatives of cellulose such as cellulose acetate, and natural fibers such as wool, silk and cotton. In some cases where the particular dye compound is only moderately water-soluble, it will be found that the addition of a dispersing agent such as a soap, a sulfonated oil or a fatty acid glyceryl sulfate is advantageous. More specifically, the dyeing operation can be conducted as follows:

2.5 parts by weight of the dye, prepared according to any of the examples described, are dissolved in 230 parts of water and the mixture heated to about 80-85° C. at which point it is maintained throughout the entire dyeing operation. Then 100 parts of a textile material such as cellulose acetate, for example, is immersed in the dye solution and worked until the color acquired is considered satisfactory. Salt may be added during the dyeing operation to promote exhaustion of the dye bath. The material is then removed from the bath, washed with soap, rinsed and dried. It will be colored green to blue shades depending on the particular dye compound employed.

While our invention has been illustrated more particularly in connection with cellulose acetate, wool and silk, it will be understood that our new phosphated azine compounds are likewise applicable as dyes for other cellulosic derivatives including the hydrolyzed as well as the unhydrolyzed organic acid esters of cellulose and mixed organic acid esters of cellulose such as cellulose formate, cellulose acetate, cellulose propionate, cellulose butyrate, cellulose phthalate, cellulose acetate-propionate, cellulose acetate-butyrate and cellulose ethers such as methyl cellulose, ethyl cellulose, benzyl cellulose, and the like.

We claim:

1. The azine compounds selected from the group consisting of a phenothiazine nucleus, a phenoxyazine nucleus, a phenazine nucleus, and an α , γ -dibenzophenazine nucleus, each of said nuclei containing as nuclear carbon atom substituents at least one alkylamino group and at least one acid ester of phosphorus group joined to the omega carbon atom of a non-cyclic organic sidechain.

2. The azine compounds having the general formula:

wherein Z_1 represents the non-metallic atoms necessary to complete a benzene nucleus, Z_2 represents the non-metallic atoms necessary to complete an aryl nucleus selected from the group consisting of a benzene nucleus, a naphthalene

nucleus, and a phenanthrene nucleus, and X represents a member selected from the group consisting of an atom of oxygen, an atom of sulphur, an atom of nitrogen, and an imide group, and wherein Z_1 contains at least one alkylamino group, and Z_1 and Z_2 together contain at least one acid ester of phosphorus group joined to the omega carbon atom of a non-cyclic organic sidechain.

10 3. The azine compounds selected from the group consisting of a phenothiazine nucleus, a phenoxyazine nucleus, a phenazine nucleus, and an α , γ -dibenzophenazine nucleus, each of said nuclei containing as nuclear carbon atom substituents at least one alkylamino group and at least one acid ester of phosphorus group having the general formula:

wherein n is selected from the group consisting of zero and the numeral 1, R_1 and R_2 each represents a member selected from the group consisting of an amino group, an alkylamino group, and the group $-OZ$, wherein Z represents a member selected from the group consisting of hydrogen, an alkyl group, and an alkali forming metal, the said acid ester group being joined to the omega carbon atom of a non-cyclic organic sidechain.

25 4. The azine compounds selected from the group consisting of a phenothiazine nucleus, a phenoxyazine nucleus, a phenazine nucleus, and an α , γ -dibenzophenazine nucleus, each of said nuclei containing as nuclear carbon atom substituents at least one alkylamino group and at least one acid ester of phosphorus group joined to the omega carbon atom of an alkylamino group.

30 5. An organic derivative of cellulose textile material colored with a dye selected from the group of azine compounds consisting of a phenothiazine nucleus, a phenoxyazine nucleus, a phenazine nucleus, and an α , γ -dibenzophenazine nucleus, each of said nuclei containing as nuclear substituents at least one alkylamino group and at least one acid ester of phosphorus group joined to the omega carbon atom of a non-cyclic organic sidechain.

35 6. A cellulose acetate textile material colored with a dye selected from the group of azine compounds consisting of a phenothiazine nucleus, a phenoxyazine nucleus, a phenazine nucleus, and an α , γ -dibenzophenazine nucleus, each of said nuclei containing as nuclear substituents at least one alkylamino group and at least one acid ester of phosphorus group joined to the omega carbon atom of a non-cyclic organic sidechain.
